(57) **CLAIM**

The ornamental design for an electrical female terminal, as shown and described.

DESCRIPTION

FIG. 1 is a top and front perspective view of an electrical female terminal in accordance with the present invention; FIG. 2 is a top and back perspective view of the electrical female terminal in FIG. 1;

FIG. 3 is a left side elevational view thereof;

FIG. 4 is a right side elevational view thereof;

FIG. 5 is a top elevational view thereof;

FIG. 6 is a bottom elevational view thereof;

FIG. 7 is a front elevational view thereof, and

FIG. 8 is a back elevational view thereof;

FIG. 9 is a top and front perspective view of another embodiment of an electrical female terminal in accordance with the present invention;

FIG. 10 is a top and back perspective view of the electrical female terminal in FIG. 9;

FIG. 11 is a left side elevational view thereof;

FIG. 12 is a right side elevational view thereof;

FIG. 13 is a top elevational view thereof;

FIG. 14 is a bottom elevational view thereof;

FIG. 15 is a front elevational view thereof; and,

FIG. 16 is a back elevational view thereof.

The broken lines in the drawings depict portions of the electrical female terminal that form no part of the claimed design.
